UNITED STATES PATENT OFFICE.

ELIAS N. MILLER, OF AMARILLO, TEXAS.

DIE MECHANISM.

Application filed September 21, 1926. Serial No. 136,852.

This invention relates to wire twisting machines and more particularly to a die mechanism for use in connection therewith, and it is primarily an object of the invention to provide a machine or mechanism of this kind especially designed and adapted for use in the production of wire ties of the general character disclosed in my Patent No. 1,577,343 dated March 16, 1926.

It is also an object of the invention to provide a die mechanism including a base plate and a die member arranged thereon together with means operating to hold against displacement the work engaged with the wire.

Another object of the invention is to provide a die mechanism of this kind constructed in a manner wherein a plurality of dies may be interchangeably and selectively used, each of such dies being of a form or type as may be required with work of a particular character.

The invention consists in the details of construction and in the combination and arrangement of the several parts of my improved die mechanism whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in top plan illustrating a die mechanism constructed in accordance with an embodiment of my invention and in applied position with respect to a twisting machine, parts being broken away;

Figure 2 is a view in side elevation with parts in section of the structure illustrated in Figure 1;

Figure 3 is a view in top plan of one of the die members shown in the succeeding figures;

Figure 4 is a side elevation of the die member shown in Figure 3;

Figure 5 is a view in plan of a modified form of die member;

Figure 6 is a view in side elevation of the die member shown in Figure 5;

Figure 7 is an enlarged view partly in side elevation and partly in section of a die mechanism, a second position of the loop member being indicated by broken lines;

Figure 8 is a view in top plan, with a part broken away of the structure illustrated in Figure 7, a second position of the loop member being also indicated by broken lines;

Figure 9 is a sectional view taken substantially on the line 9—9 of Figure 8;

Figure 10 is a view in top plan illustrating another design of die member;

Figure 11 is a view in front elevation of the member illustrated in Figure 10.

As disclosed in the accompanying drawings, M denotes a portion of a wire twisting machine which may be of any desired type and which includes a head H and a shaft S in desired spaced relation with respect to said head H, said shaft being adapted to be rotated in any desired manner. It is to be understood, however, that I do not limit myself to a wire twisting machine embodying these particular or specific features.

The head H and the shaft S are each provided with an elongated base plate 1 provided along its side marginal portions with the grooves or channels 2 in which are engaged the inwardly directed flanges 3 carried by the side walls 4 of a loop member L.

The body or main plate 5 of this loop member L is spaced a desired distance from the opposed face of the plate 1 when the loop member L is in applied position. The construction and mounting of the loop member L is such that the same may be readily moved or slid along the base plate 1 for a purpose to be hereinafter more particularly referred to.

The outer portion of one, or both if preferred, of the plates 1 is reduced in thickness from one face a to provide a lip or extension 6. This lip or extension 6 in its upper part has disposed therethrough an opening 7. This face a inwardly of the lip or extension 6 is provided with a depression or pocket 8 which is adapted to receive the body or base

plate 9 of a die member D. Carried by this plate 9 is a forming head 10 which is to be of the configuration or design in accordance with the character of the work required and this head preferably extends beyond a margin of the plate 9 to overlie the face *a* of the plate 1 in advance of the depression or pocket 8.

The die member D is held in applied position by a tap screw 11 selectively disposed through one of the openings 12 in the plate 1 and in requisite engagement with the die member D. A plurality of openings 12 are employed to provide desired fastening to the plate 1 of die members D of different lengths.

It is preferred that the under face of the plate 5 be provided with a channel or groove 14 to partially receive the inner portion of a die head 10 when the loop member L is moved into a position to overlie an applied die member D. The width between the side walls 4 is greater than the major width of a die head 10 in order to assure requisite clearance *b* at opposite sides of such head when the loop member L is in working position with respect thereto.

The dies constructed in accordance with my invention are particularly adapted for use in the production of wire ties of the type disclosed in my Patent No. 1,577,343 hereinbefore referred to.

In Figures 5 and 6 I illustrate a further type or style of die member D' wherein the forming head 10' is relatively short in length, while in Figures 10 and 11 I illustrate a still further type of die member D''. It is to be understood that these die members may be of such design or type as may be required for the particular character of the work or more particularly the design of eye required in the wire tie.

In practice, the wire from which a tie T is to be formed is properly disposed around the forming members 10 with one extremity of the wire directed through an opening 7. After this has been done a loop member L is moved over its associated forming head whereupon the twisting machine is caused to operate. During this operation each of the loop members L serves to prevent the eye 15 being formed in the tie T from becoming disengaged from its forming head 10. It will also be understood that each eye 15 will be formed in a style or design similar to the character of the forming head 10.

From the foregoing description it is thought to be obvious that a die mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do

not wish to be understood as limiting myself to the precise arrangement and formation of the several parts herein shown in carrying out my invention in practice except as hereinafter claimed.

70

I claim:—

1. A die structure for forming eyes in a wire tie comprising a base plate, a die member, means for detachably connecting the die member to the plate, said die member having an outwardly arranged forming head around which a strand of wire is adapted to be disposed, and a loop member slidably engaged with the base plate and adapted to be moved over the forming head when the die member is applied.

75

2. A die structure for forming eyes in a wire tie comprising a base plate, a die member, means for detachably connecting the die member to the plate, said die member having an outwardly arranged forming head, and a loop member slidably engaged with the base plate and adapted to be moved over the forming head when the die member is applied, said base plate in advance of the applied die member being provided with an opening, a wire strand being adapted to be disposed around the forming head with an extremity engaged within the opening of the base plate in advance of the applied die member.

80

3. A die structure for forming eyes in a wire tie comprising a base plate having grooves disposed along its marginal edges, a loop member having inwardly directed flanges engaging within the grooves of the base plate permitting the loop member to have sliding movement along the base plate, a die member including a base plate and an outstanding forming head, said first named base plate being provided with a recess to receive the base plate of the die member, and means for holding the die member to the first named base plate, said loop member being movable to overlie the forming head carried by the base plate of the die member.

85

4. A die structure for forming eyes in a wire tie comprising a base plate, a die member, means for detachably connecting the die member to the plate, said die member having an outwardly arranged forming head, and a loop member slidably engaged with the base plate and adapted to be moved over the forming head when the die member is applied, said loop member providing clearance at the opposite sides of the forming head of the die member when said loop member overlies an applied die member.

90

5. A die structure for forming eyes in a wire tie comprising a base plate, a die member, means for detachably connecting the die member to the plate, said die member having an outwardly arranged forming head, and a loop member slidably engaged with

120

130

the base plate and adapted to be moved over the forming head when the die member is applied, said loop member providing clearance at the opposite sides of the forming head of the die member when said loop member overlies an applied die member, an inner face of the die member being pro-

vided with a channel to partially receive the forming head when the loop member is in a position to overlie the applied die member. ¹⁰

In testimony whereof I hereunto affix my signature.

ELIAS N. MILLER.
